(57) CLAIM

The ornamental design for a toilet brush, as shown and described.

DESCRIPTION

FIG. 1 is a perspective view of a toilet brush, showing our new design.

FIG. 2 is a front view thereof;

FIG. 3 is a left view thereof;

FIG. 4 is a right view thereof;

FIG. 5 is a top view thereof;

FIG. 6 is a bottom view thereof;

FIG. 7 is another perspective view thereof;

FIG. 8 is yet another perspective view thereof; and,

FIG. 9 is still another perspective view thereof.

In the drawings, the broken lines are for the purpose of illustrating portions of the toilet brush that form no part of the claimed design.
